(57) CLAIM

The ornamental design for a video game controller, as shown and described.

DESCRIPTION

FIG. 1 is an isometric view taken from the front, top right-side perspective view of a video game controller showing our new design;

FIG. 2 is a front plan view thereof;

FIG. 3 is a bottom view thereof;

FIG. 4 is a right side view thereof;

FIG. 5 is a top view thereof;

FIG. 6 is a left side view thereof; and,

FIG. 7 is a back plan view thereof.

In the drawings, the broken lines depict environmental subject matter only and form no part of the claimed design.
